UNITED STATES PATENT OFFICE.

JOHN WILLIAM NASMITH, OF MANCHESTER, ENGLAND.

COMB IN COMBING MACHINES.

Application filed March 10, 1926, Serial No. 93,640, and in Great Britain March 17, 1925.

These improvements relate to the combs employed in machines for the combing of textile fibres, as for instance the Nasmith's cotton combing machine, although from the 5 details hereinafter given the application of the improvements to any comb the function of which is to clean and comb any textile fibre which is presented to it will be readily understood. The object of the improvements is to provide needles of a lesser number per unit length of comb than hitherto provided thus allowing of stronger needles being used, with a lesser number of points to engage with the lap or fleece or the like 10 of fibres as a natural consequence, whilst not impairing in any way the efficiency of the comb. The latter is thus adapted to deal adequately with heavy work, a desideratum in up-to-date apparatus with a high rate of 15 production.

Hitherto the comb needles of a top comb in a cotton combing machine have in one form been made conical throughout, and the effective fibre cleaning space is only that 20 space between needles which is adjacent to the lower edge of the comb blade, that is to say, at the narrowest point of the said space between needles and into which the lap is pulled at the beginning of the detaching operation, in a cotton comber whilst the necessary large number of points per inch offer 25 much resistance to the entry of the lap especially when the short fibre is being combed. The needles of such a comb are necessarily fragile when large quantities of 30 fibre have to be dealt with.

To strengthen the needles, they have also hitherto been made with adjacent sides flattened, but a flattened surface is not so efficient for the purpose as the surface of a cylinder or cone, and strength in this form of needle is gained at the expense of efficiency. Further, as the needles have necessarily to be attached to the comb blade with 40 their longer transverse axes parallel to the path of the fibres, efficient fitting of the needles presents a difficulty.

According to my present improvements I form a comb with a plurality of needles 45 which are parallel to each other and each of which is cylindrical for a part of its

length, the rest of the needle being conical, the apex of the cone forming the point of the needle.

The improvements will now be fully described with reference to the drawing annexed which drawing is a fragmentary elevation of a comb blade with some needles fixed thereon. The comb blade *b* has the needles attached to it in known manner, the 55 upper portion *c* of each needle being in the form of a cylinder, whilst the lower portion *d* tapers off in conical form. By this construction there is a large aggregate area per unit length of comb between the conical 60 portion *d* for easy entrance into the lap or fleece of fibres, and the cylindrical portions of the needles being parallel the whole of the space *e* between any two adjacent needles is effective cleaning space for the fibres. 65 With approximately thirty needles of the type shown in the drawing per inch of blade in a top comb, the effective cleaning space of the said comb is equal to that of a comb with needles wholly conical in 70 form, fitted seventy to the inch and of a greater length in proportion to their mean diameters than the needles shown in the drawing. That is to say, there is more room left per inch length of blade which 75 may be occupied by needle material, allowing for the fitting of stronger needles, this added strength permitting the use of longer needles whilst the spaces between the conical ends of the needles made according to 80 these improvements allow easy entrance of the lap or fleece, there being fewer points 85 to resist the said entrance of the lap or fleece. Further, the cylindrical form of the portion *c* of a needle facilitates attachment 90 of the said needle to the comb blade *b*, by the usual soldering or like methods.

A convenient space *e* between the cylindrical portions of two adjacent needles is two one-thousandths of an inch.

I claim:—

1. A comb for a combing machine, comprising a blade, and a series of combing teeth secured against one side of the blade and having straight cylindrical combing 100 portions spaced apart and arranged parallel to each other and projecting below the

edge of the blade and terminating in conical pointed ends.

2. A comb for a combing machine, comprising a blade, and a series of straight cylindrical combing teeth terminating in conical pointed ends, the said teeth being spaced apart and having their upper portions se-

cured against one side of the blade, and having their lower cylindrical combing portions and conical pointed ends projecting 10 below the edge of the blade.

In testimony whereof I have hereunto set my hand.

JOHN WILLIAM NASMITH.
